UNITED STATES PATENT OFFICE.

ERASTUS E. WADSWORTH, OF BOSTON, MASSACHUSETTS, ASSIGNOR TO THE ECO MAGNETO CLOCK COMPANY, OF BOSTON, MASSACHUSETTS, A CORPORATION OF MAINE.

WATCHMAN'S TIME-DETECTOR.

1,140,859.

Specification of Letters Patent.

Patented May 25, 1915.

Application filed February 11, 1915. Serial No. 7,631.

To all whom it may concern:

Be it known that I, ERASTUS E. WADSWORTH, of Boston, in the county of Suffolk and State of Massachusetts, have invented 5 certain new and useful Improvements in Watchmen's Time-Detectors, of which the following is a specification.

This invention relates to portable clocks, or watches, of the character used by watchmen to make records of the time when the watchman visits the predetermined localities which he is required to cover in his beat. 10

The invention is illustrated in the accompanying drawings as employed in connection with a device of this character which is disclosed in Letters Patent No. 857,985, granted June 25, 1907, to G. B. Fessenden.

For the purpose of insuring detection of any attempt to make the watchman's record 20 in any manner other than the prescribed method, several devices have heretofore been produced, which, when the lid or cover of the casing of the device is opened or closed, will cause the cutting of a slit in a 25 marginal portion of the dial. The object of doing this is so well understood that further explanation thereof is unnecessary.

The object of my present invention is to provide a combined "tell-tale" and lock, the 30 device being so constructed that whenever the casing is unlocked preparatory to opening, the "tell-tale" will be released so that the ensuing lift of the cover will leave a mark, such as a marginal slit in the paper 35 dial employed.

With these and further objects in view, my invention consists in the improvements which I shall now proceed to describe and claim.

40 Of the accompanying drawings: Figure 1 is a plan view of a watchman's clock or time-detector having my improvements, a portion of the cover being broken away. Fig. 2 is an elevation of a portion of the casing, 45 showing my improvements by dotted lines. Fig. 3 represents a section on line 3—3 of Fig. 2. Fig. 4 is an elevation of the two members of my combined "tell-tale" and lock.

50 Similar reference characters indicate similar parts in all of the views.

The case, which, of course, contains the usual kind of clock or time movement employed in devices of this character, has a

cover or lid hinged thereto, as at 12. The 55 time-operated stem 13 of the clock movement has any suitable or preferred means for removably securing thereto a paper dial 14. The usual top plate of the watch or clock movement casing is indicated at 15, 16 being a guide or stripper, between which and the plate 15 the dial 14 is rotated by the clock movement. The stripper 16 preferably has a tip 17 formed as a pointer.

Above the slot in the casing 10 for the 65 entrance of the key which is to unlock or lock the casing, the plate 15 is formed with a marginal slot 18. This slot is bridged by a holder or stripper 19, which is here shown as a length of wire bent as indicated in the 70 drawings and secured in place by screws 20.

A tongue 21, having a base 22 which is secured to the inside of the cover or lid, has its lower end extending laterally to provide 75 a shoulder 23 which acts as a keeper for the lock presently described. The extreme end of the lateral portion of the tongue is formed somewhat diamond shape, the upper and lower edges being sharpened, this portion serving as a "tell-tale" or dial-edge muti-lator whenever the cover is raised or lowered. The object of the stripper 19 is to render it certain that the margin of the dial will be held while the marker 24 moves upwardly through the dial. When the marker 85 moves downwardly, the dial is first slightly flexed until arrested by the plate 15, the sides of the slot 18 holding the paper while the marker passes through. The knife is thus adapted to cut in two directions, a 90 record being made of each opening and closing of the door.

The key-operated locking mechanism includes a bolt 25 formed as a portion of a slide 26, having a notch or recess 27 to be 95 engaged by the usual portion of a key employed for locking and unlocking the casing. The slide is formed with two slots 28 mounted on pins 29. Fig. 2 illustrates by full and dotted lines the two positions to which the 100 slide and the locking bolt 25 may be moved by a suitable key inserted through the key-hole represented in Fig. 2. When the slide is moved to the dotted line position, the cover may be immediately opened, the upward movement of the marker 24 causing the cutting of a slit in the margin of the dial. This marking is necessarily at a defi- 105

nite point, and the stripper 16 is so mounted or secured in the casing that its pointer 17 is located at such a distance from the radial line of the dial which will be slotted, as to measure three hours of time. This is indicated by the space of the heavier radial lines in Fig. 1. The object of this special space of the members 16 and 24 is that when the employer places a new dial in the casing, he so locates the dial rotatively that the time when he does it will be indicated by the pointer 17. He immediately closes and locks the cover, knowing that his so doing will slit the margin of the dial just three hours away. 15 Later when he opens the casing to remove the dial which has been in place during the use of the device by the watchman, his opening of the cover to remove the record makes another slit three hours away from the time 20 when he opens the lid. If now the record shows any other slits than these two, or shows any slits other than the employer knows should exist, it is evidence that the device has been tampered with, or, at least, 25 that the cover has been opened by someone else than the employer.

I claim:

1. A device of the character described, comprising a two-part casing, a dial-rotating mechanism contained therein, one of the parts of the casing having a projection to mark the dial, and a key-operated member carried by the other part of the casing and

adapted to interengage said projection to lock the casing. 35

2. A device of the character described, comprising a casing having a hinged cover, a tongue rigidly connected with the cover, said tongue having a dial mutilator, a dial-rotating mechanism in the main portion of the casing, and a key-operated member carried by said main portion adapted to engage a portion of said tongue to lock the cover in closed position. 40

3. A watchman's clock comprising a case having a hinged cover, a time-operated dial in the case, a dial marker carried by the cover and having a shoulder, and a key-operated member adapted to engage said shoulder to hold the cover locked. 45

4. A watchman's clock comprising a case having a hinged cover, a tongue projecting downwardly from the cover, said tongue having a laterally extending portion, the end of which has cutting edges, and a slide mounted in the case and adapted to be operated by a key, said slide having a portion formed to cross over a portion of the tongue adjacent to the cutting portion, to hold the cover locked. 50

In testimony whereof I have affixed my signature, in presence of two witnesses.

ERASTUS E. WADSWORTH.
